FISH BOWL

Earl A. Rice, Mercersburg, Pa.

Application May 25, 1949, Serial No. 2,886

Term of patent 14 years

(Cl. D91—2)

To all whom it may concern:

Be it known that I, Earl A. Rice, a citizen of the United States, residing at Mercersburg, in the State of Pennsylvania, have invented a new, original, and ornamental Design for a Fish Bowl, of which the following is a specification, reference being had to the accompanying drawing, forming a part thereof.

In the drawing:

Fig. 1 is a front elevational view of a fish bowl, showing my new design.

Fig. 2 is a plan view.

Fig. 3 is an elevational view of the back of the fish bowl.

Figure 4 is an end elevational view.

I claim:

The ornamental design for a fish bowl, as shown.

EARL A. RICE.
